Primary Examiner — Eric Goodman*Assistant Examiner* — Megan M Majcher Hartnett(74) Attorney, Agent, or Firm — Joseph V. Saphia; Frommer Lawrence & Haug LLP(57) CLAIM

The ornamental design for a display screen or portion thereof with graphical user interface, as shown and described.

DESCRIPTION

The sole FIGURE is a front view of a display screen or portion thereof with graphical user interface showing a new design. The outermost box in broken lines in the FIGURE illustrates the perimeters of a display screen or portion thereof and forms no part of the claimed design.

Subject matters in broken lines in the FIGURE, such as text boxes texts, words, letters, symbols, icons, numbers, images, and/or lines, form no part of the claimed design.

1 Claim, 1 Drawing Sheet(56)
